UNITED STATES PATENT OFFICE.

JOHANN G. PETERSON, OF JERSEY CITY, NEW JERSEY, ASSIGNOR TO MANHATTAN ELECTRICAL SUPPLY COMPANY, OF JERSEY CITY, NEW JERSEY, A CORPORATION OF NEW JERSEY.

ELECTRIC LANTERN.

1,168,826.

Specification of Letters Patent. Patented Jan. 18, 1916.

Application filed May 28, 1915. Serial No. 30,885.

To all whom it may concern:

Be it known that I, JOHANN G. PETERSON, a citizen of the United States, residing at Jersey City, in the county of Hudson and 5 State of New Jersey, have invented certain new and useful Improvements in Electric Lanterns, of which the following is a specification.

This invention relates to electric lanterns, 10 among the principal objects of the invention being the provision of an article of this nature which is simple in construction, susceptible of inexpensive manufacture, the parts of which can be readily assembled and 15 which has means of an effective character to prevent accidental movement of a circuit controlling or switching member from off to on position, which latter is of importance during shipment of the device.

20 The invention comprises other features of novelty and advantage, which with the foregoing will be stated at length in the following description wherein I will set forth in detail that one of the several forms of embodiment of the invention which I have selected for illustration in the drawings accompanying and forming part of the present specification. I do not restrict myself to this disclosure; I may depart therefrom 25 in several particulars within the scope of the invention defined by the claims following said description.

Referring to said drawings:

Figure 1 is a top plan view of a lantern 35 involving my invention, the cover being removed. Fig. 2 is a longitudinal section on the line 2—2 of Fig. 1, looking in the direction of the arrow and showing the cover in position. Fig. 3 is a view on the same section line 2—2 of the lamp and certain of its adjuncts. Fig. 4 is a detail view showing the shell which receives the lamp, which is removed, the manner of mounting the shell and certain other parts. Fig. 5 is a section 40 detail of the circuit controlling or switching member, a portion of the cover being also illustrated. Figs. 6 and 7 are cross sectional views on the line 6—7 of Fig. 5 looking in the direction of the arrow, Fig. 5 showing the circuit controlling member in 45 two positions by full and dotted lines, and Fig. 7 representing said member in the on position.

Like characters refer to like parts 55 throughout the several views, Figs. 3 to 7

inclusive being on a larger scale than Figs. 1 and 2.

The lantern comprises a suitable source of electrical energy such as the battery 2 which as shown consists of the well-known dry cell. This battery is preferably suitably incased and protected, and the box or can 3 answers satisfactorily in this connection. As represented the box or can is equipped with a removable cap or cover 4. The body of the box or can is preferably of conducting material such for instance as tin, so that it presents part of the lamp circuit. While it is not imperative that the cover or cap 4 should be of metal, it is conveniently made of this substance, and as will be inferred, tin is suitable for the purpose. The box or can 3 may be provided with a suitable handle such as the bail 5, only a part of which, however, is shown (Fig. 1). Said bail is connected 75 with the body of the box or can 3.

The lamp is denoted by 6 and it has the customary contact shell 7 and the central end contact 8. As shown the contact shell is screwed into the contact shell or tube 9 provided at its inner end with a circumferential circular flange 10 fitted against and in electrical contact with the inturned annular flange 11 of the approximately frusto-conical lamp and reflector case 12 of metal, brass answering the necessary requirements. This flange 11 fits against and is in electrical contact with the box or can 3, and the means for holding the case 12 in position will be herein-after described. Associated with the lamp 6 90 is the reflector 13 and lens 14, both carried by the case 12.

Inside the box or can 3 is a contact as 15 shown as resilient and which can be formed up conveniently from sheet metal. Said contact member 15 is disposed between the battery or cell 2 and the inner wall of the box or can 3, the free portion thereof extending upwardly above the top of the battery to operate with a second contact as will herein-after more particularly appear. Between the contact member 15 and the box or can 3 is interposed a strip of insulating material such as 16; fiber presents a suitable substance in this regard. Also disposed between the cell 2 and the box or can 3 is an attaching member such as the plate 17. Between this plate 17 and the butt portion of the contact member is a piece of insulation as 18, and fiber may be provided for this purpose. As 110

shown the butt portion of the contact member 15 has lugs 19 bent over the upper and lower edges of the insulation 18. The plate 17 as represented is provided with peripheral 5 projections 20 extending through registering openings in the insulation 18, butt portion of the contact member 15; insulation 16, can 3, and flanges 11 and 10, the forward ends of these projections 20 being bent over the front 10 face of the flange 10 whereby the parts mentioned can be securely and effectively held in assembled relation. The lamp 6 is so mounted that its contact end can project through openings in the can 3 and insulation 15 16, by reason of which its central end contact 8 can engage the butt portion of the contact member 15 at which time, as will be clear, the contact shell 7 of the lamp is in contact with the supporting contact shell 9. 20 Supported by the battery or cell 2 is a suitable insulating member such as the disk 21 of fiber and eyeleted or otherwise suitably connected to this insulating member 21 are the contact members 22 and 23, the body of 25 the contact member 22 being longitudinally slotted to receive the screw 24 of one pole of the battery 2, while the body of the contact member 23 is slotted to receive the body of the screw 25 of the other pole or terminal 30 of the battery. The upstanding portion 22^a of the contact member 22 presents the contact proper thereof, being coöperative with the contact member 15, being as will be evident somewhat resilient. The upstanding 35 portion of the contact 23 has electrical connection, by contact, with the inner surface of the can or box 3. It will, therefore, be clear that if the lamp 6 is in position and that if the contact 15 and upstanding portion 22^a 40 of the contact 22 be bridged, the lamp will be lighted.

The circuit controlling or switching member is preferably carried by the removable cover 4 and a circuit controlling member 45 such as meets my requirements will now be described. Said circuit controlling or switching member involves in its make up the central spindle 26 extending through a hole or perforation 27 in the top 4, being 50 provided with a button or manipulating portion 28. The spindle is further provided with a circular enlargement or collar 29 fitted in said perforation or opening 27 for turning movement. The lower portion of 55 the button or finger piece 28 overlies the cover 4. The connector of the circuit controlling or switching member is denoted by 30, and it may for instance be of brass, having at its ends the lobes 31 and 32. It will 60 be noted that the lobe 31 is of greater width than the lobe 32, which presents one convenient means for preventing accidental closing of the said circuit controlling or switching member as will hereinafter more 65 particularly appear. Fitted around the

spindle 26 are the insulating pieces 33 and 34 which may be also of fiber, the lower insulating piece having the central boss 35 extending comparatively snugly into the central opening of the connector 30. The insulating pieces 33 and 34 and the connector 30 may be clamped together in any desirable manner, for instance by staking the inner or lower end of the spindle over the lower insulating part 33 as shown at 36. The spindle 26 is disposed between the resilient contacts of the contact members 15 and 22 and by turning said spindle, the connector 30 may be turned therewith to either move the connector to the open or the closed position. 70 Said connector is shown in dotted lines in Fig. 1 in the open position and in closed position in full lines in said view. In the latter position it simultaneously engages the contacts of the contact members 15 and 22 75 so as to effect the lighting of the lamp 6 if the latter be in place. The article is shipped with the circuit controlling or switching member in open position. It is subjected naturally to jars or vibration. No matter 80 in which direction it may be moved accidentally under the conditions noted or something similar, the circuit controlling member or the connector 30 thereof cannot be closed. When the connector 30 moves in one direction from the open position thereof as shown by the full lines in Fig. 6, the wide lobe 31 85 will strike the contact of the contact member 22 before the narrow lobe 32 strikes the contact of the contact member 15, whereas if the connector moves in the opposite direction or to the dotted position in Fig. 6, the wide lobe 31 will strike the contact of the contact member 15 before said narrow lobe 90 can come against the contact of the contact member 32, so that in each event the circuit cannot be closed. By turning the spindle 26 through the agency of a button 28 or its equivalent, the connector 30 can be easily 95 moved to circuit closing position as shown in Fig. 7.

What I claim is:

1. An electric lantern comprising a transportable case adapted to receive a battery therein, contacts adapted for electrical connection with the terminals of the battery, and a connector movable to electrically bridge across the contacts, the connector having lobes at its ends, one lobe being wider than the other to thereby prevent the connector simultaneously accidentally engaging both contacts. 115

2. An electric lantern comprising a case having a battery therein, contacts electrically connected with the terminals of the battery, and circuit controlling means, said circuit controlling means comprising a spindle having a collar, insulating members and a connector between the insulating members, the spindle being provided with means for 120 125 130

clamping the insulating member and the connector together with one of the insulating members against said collar, the spindle being disposed between the contacts and 5 movable to cause the connector to assume circuit opening and circuit closing positions.

3. An electric lantern comprising a case of conducting material, a lamp receiving shell in electrical connection with said case, 10 an attaching member in the case, a contact between the attaching member and the case insulated from both, the attaching member being provided with lugs extending through the case for securing said lamp receiving shell in position, a battery in the case having two contacts, one of which cooperates with said other contact and is electrically connected with one terminal of the battery, and the other of which is electrically connected with the other terminal of the battery 15 and is electrically connected with the case.

4. An electric lantern comprising a case of conducting material, a contact member in the case, insulating material between the 20 contact member and the case, a lamp sup-

porting shell exteriorly of the case, having a circumferential flange, an attaching plate in the case, insulating material between the attaching plate and the contact member, the attaching plate having projections and the 30 two pieces of insulating material and said flange having openings to receive said projections, the latter being bent over the flange to hold the several parts together, the first mentioned piece of insulating material having an opening to receive the central end 35 contact of a lamp, and a battery in the case having contacts, one of which is electrically connected with one terminal of the battery and cooperates with said contact member, 40 and the other of which is electrically connected with the other terminal of the battery and is connected electrically with said case.

In testimony whereof I affix my signature 45
in presence of two witnesses.

JOHANN G. PETERSON.
